UNITED STATES PATENT OFFICE.

OTTO LEIGH, OF NEWARK, NEW JERSEY, ASSIGNOR TO UNGER BROTHERS,
OF NEWARK, NEW JERSEY, A CORPORATION.

DESIGN FOR A BACK FOR BRUSHES OR SIMILAR ARTICLES.

SPECIFICATION forming part of Design No. 36,222, dated February 10, 1903.

Application filed July 5, 1901. Serial No. 67,254. Term of patent 3½ years.

To all whom it may concern:

Be it known that I, OTTO LEIGH, a citizen of the United States, residing at Newark, in the county of Essex and State of New Jersey, have 5 invented and produced a new, original, and ornamental Design for the Backs of Brushes or Similar Articles, of which the following is a specification, reference being had to the accompanying drawings, forming a part thereof.

10 The figure is a plan view of the back of a brush or similar article, showing my design. As shown in the drawing, the leading and essential feature of my design consists of the raised ornamentation representing the conventional form of two dragons with inwardly-curved wings disposed along opposite edges of the back at its upper portion. The flamboyant tails of the dragons extend downwardly along the two edges of the back and

join the scrolled tails of two oppositely-disposed raised conventional representations of dolphins, the closely-approached heads of which, at the lower part of the back, complete the design of the border of the back proper. From the mouths of the dolphins 25 scrolled bands extend over the handle to a Medusa head at the lower end of the latter.

Having thus described my invention, what I claim as new, and desire to secure by Letters Patent, is—

30 The ornamental design for the back of a brush or similar article, as herein shown and described.

OTTO LEIGH.
